UNITED STATES PATENT OFFICE.

JAMES B. WALKER, OF RUSH SPRINGS, INDIAN TERRITORY.

DESIGN FOR A RAIL-BRACE AND TIE-PLATE.

SPECIFICATION forming part of Design No. 31,413, dated August 15, 1899.

Application filed July 15, 1899. Serial No. 724,004. Term of patent 7 years.

To all whom it may concern:

Be it known that I, JAMES B. WALKER, a citizen of the United States, residing at Rush Springs, in the Chickasaw Nation, Indian Territory, have invented and produced a certain new and original Design for a Rail-Brace and Tie-Plate; and I do declare the following to be a full, clear, and exact description of the invention, such as will enable others skilled in the art to which it appertains to make and use the same.

The invention relates to a new and original design for a rail-brace and tie-plate; and it consists of a design of the configuration shown in the accompanying drawings, in which—

Figure 1 is a perspective view. Fig. 2 is a longitudinal sectional view. Fig. 3 is a cross-sectional view.

The leading feature of the design comprises the plate 1, one end of which is provided with

a projecting tongue 2, having rising therefrom and extending inwardly an inclined housing 3, which has a portion of its lower edges 4 projecting above and over the plate 1, the apertures 5 arranged in rectangular order, and the aperture 6 at the rear of the housing. The under side of the plate is provided with two downwardly-projecting lugs 7, formed with inclined edges 8.

What I claim is—

The design for a rail-brace and tie-plate as herein shown and described.

In testimony whereof I have hereunto set my hand in presence of two subscribing witnesses.

JAMES B. WALKER.
